FACE MASK

Steve P. Vorves, 20970 Delaware,
Southfield, Mich. 48075

Filed Mar. 20, 1967, Ser. No. 6,292

Term of patent 14 years

(Cl. D86—10)

FIG. 1

FIG. 2

FIG. 3

The characteristic features of my design reside in the portions shown in full lines in the drawing a conventional handle shown in broken lines.

I claim:

The ornamental design for a face mask, as shown and described.
